DISPENSING CASING

Filed Dec. 4, 1937

FIG. I.

FIG. II.

FIG. III.

INVENTOR:

ERIC H. BRADLEY,

BY Arthur E. Paige
Atty.

UNITED STATES PATENT OFFICE

108,063

DESIGN FOR A DISPENSING CASING

Eric H. Bradley, Spring Lake, Mich., assignor to
John Wood Manufacturing Company, Inc.,
Conshohocken, Pa., a corporation of Delaware

Application December 4, 1937, Serial No. 73,375

Term of patent 14 years

To all whom it may concern:

Be it known that I, Eric H. Bradley, a citizen of the United States, residing at Spring Lake, in the county of Ottawa and State of Michigan, have invented a new, original, and ornamental Design for Dispensing Casings, of which the following is a specification, reference being had to the accompanying drawing, forming part thereof.

In said drawing; Fig. I is a front elevational view of a dispensing casing, showing my new design. Fig. II is a side elevational view thereof. Fig. III is a plan view of said casing.

I claim:

The ornamental design for a dispensing casing, as shown. .

ERIC H. BRADLEY.
